THE MORRIS PETERS CO., PHOTO-LITHO., WASHINGTON, D. C.

UNITED STATES PATENT OFFICE.

JAMES ALFRED PUGH, OF CARDIFF, WALES.

PERSONAL EQUIPMENT FOR CARRYING PURPOSES.

1,230,025.

Specification of Letters Patent. Patented June 12, 1917.

Application filed September 21, 1916. Serial No. 121,492.

To all whom it may concern:

Be it known that I, JAMES ALFRED PUGH, a subject of the King of England, residing in Cardiff, Wales, have invented certain new and useful Improvements in Personal Equipments for Carrying Purposes, of which the following is a specification.

This invention relates to improvements in personal equipment for carrying purposes and has for its object to protect the body of the wearer and give easy carriage to any weights which may be carried.

According to this invention there is provided, for personal wear, a pneumatic pad or system of pads attached to a garment of the wearer in such manner as to support the load carried by the wearer. It is particularly applicable for use in combination with harness, such as a military web equipment, but it will be appreciated that it may also be used in other circumstances.

In a preferred arrangement, the invention takes the form of a system of pneumatic pads comprising two pads adapted to rest one on each shoulder and flexible tubes, preferably fitted with non-return valves, whereby they may be inflated when in position; a third pad arranged at the small of the back of the wearer may also be provided together with a flexible tube or tubes for inflating it. For example it may be connected by separate tubes to each of the smaller pads.

According to another feature of the invention the pads or any of them are ventilated by corrugating the side which faces the body of the wearer, so as to permit the free circulation of air.

The accompanying drawings show one arrangement of the invention;

Figure 1 shows the complete system,

Fig. 2 is a section on the line X—Y of Fig. 1, and Fig. 3 is a back view showing the application of this invention to a military tunic.

Referring to the drawings, p p indicate two small pads which are intended to rest on the shoulders of the wearer. Tubes t t are attached to these pads at one end and fitted with mouth-pieces M M through which the pads may be inflated. Preferably these mouth-pieces are fitted with non-return valves, but any other type of valve may be used.

55 The small pads p p are each connected by a tube T to a large pad P which is adapted

to rest on the back of the wearer at or near the waist. This large pad is inflated by means of the tubes T , the necessary air passing through the smaller pads p .

As above stated the pads are corrugated to provide ventilation, and the arrangement is shown in Fig. 2 as applied to the pad P . The lines c c^1 on Figs. 1 and 2 show the positions of the depressions formed in one surface of the pad P . These depressions may be formed in any convenient manner, as for example by securing one wall of the pad to the opposite wall, so that when it is inflated the wall bulges outward between the depressions. These corrugations are formed on the side of the pad which lies against the wearer's body so as to provide passages permitting the circulation of air between the pad and the wearer's body.

These pads are preferably inclosed in pockets formed in or on a garment of the wearer; when this invention is used with a military web equipment the pockets are formed in the service jacket or tunic, one pocket being situated at each shoulder and one on the back just above and clear of the waist-belt. The pockets are so disposed that when the pack is placed upon the soldier's back the whole weight of the equipment rests on the pads, that is to say on the pads on the shoulder and on the pad at the back. The pads are made of rubber or other suitable material and are inflated by blowing in at the mouth-pieces M M or by means of a pump.

The pads can, if required, be attached separately or jointly to any part of the equipment or clothes either on the inside or on the outside. The connecting tubes to the pads are carried over each shoulder and are of sufficient length to be easily raised to the mouth when it is desired to inflate the pads.

The tubes can if desired be given any length and size so as to constitute pads which can alleviate pressure or friction caused by any part of the equipment on the wearer.

There may also be provided a pneumatic tube fixed inside the waist-belt, being carried in a pocket fastened to the belt by loops or any other convenient means. This pad is preferably corrugated in the manner above described.

It will be appreciated that by the use of these pneumatic pads the equipment is kept away from the body and air is allowed to

pass freely between the body and the equipment thereon.

The body is thus kept cool and at the same time friction by the close and tightly fitting straps on the shoulder and waist-belt is avoided. The pads also give elasticity to the burden carried and give loose and unfettered use of the arms, since there is no pressure of sharp edges of the equipment 10 against the shoulders. Finally, only one size of this apparatus is required to fit any wearer.

It has before been proposed to provide inflated cushions in garments for the purpose of serving as floats to keep the wearer afloat when in the water, but such cushions were disposed across the back and chest of the wearer, and it will be appreciated that the present invention differs entirely from 15 such arrangements, although it is one of

the advantages of the present invention that the device also serves as a float in addition to its main function as above set forth.

What I claim as my invention and desire to secure by Letters Patent is:—

Personal equipment comprising a pneumatic waist-belt, a pneumatic back-pad parallel with the waist-belt, two pneumatic shoulder-pads, all corrugated on that one of their faces which is presented toward the 20 wearer in use, and air-pipes connecting the back-pad with the waist-belt and with the shoulder-pads respectively.

In testimony whereof I have signed my name to this specification in the presence of 25 two subscribing witnesses.

JAMES ALFRED PUGH.
